O. C. NELSON ET AL

AUTOMATIC STOP FOR AUTOMATIC CONTROLLED MOTORS

Filed August 4, 1923

UNITED STATES PATENT OFFICE.

OTTO C. NELSON AND NORRIS E. NELSON, OF SEATTLE, WASHINGTON.

AUTOMATIC STOP FOR AUTOMATIC-CONTROLLED MOTORS.

Application filed August 4, 1923. Serial No. 655,765.

The invention is a simple and efficient means for automatically or manually stopping an automatic or button controlled motor by using a low voltage or auxiliary current which will instantly return all of the switches to the position ready for starting.

An object of this invention is to provide a means for making or breaking a circuit, operated by a battery or other low voltage current, for use with automatically controlled motors in shops and on machines and in such places as where a current of high voltage is used and it is desired to break, or make, as the case may require, the circuit which causes the motor to stop, from a remote point or any position, or any number of points, where it is not desirable or possible to carry a high voltage current.

A further object in this invention is to provide a simplified and more sensitive means to stop an automatically controlled motor from a remote point or any position or any number of points.

Another object of this invention is to utilize standard stock and easily purchasable elements in the construction of a device of this character.

Another object of this invention is to provide a device of this character which automatically breaks the local magnetic circuit when the motor is stopped.

Another object of this invention is to provide a simple and efficient method for automatically stopping an automatic or button controlled motor as trouble develops in the machine or shop.

And a further object of the invention is to provide an auxiliary or low voltage circuit for making or breaking a secondary circuit and a means for breaking the controlling circuit of the motor as the secondary circuit is made or broken.

And a still further object of this invention is to provide a simple and efficient method for breaking the main circuit of an automatic or button controlled motor by a magnet or solenoid operated by a low voltage current which will instantly return all of the switches to the starting position.

With these ends in view the invention embodies a magnetically controlled switch or relay for breaking the circuit of a motor, a low voltage circuit provided with suitable switches for energizing the magnet or relay as trouble develops in the line, an automatic means for breaking this circuit as the motor

is stopped, a bank of switches for determining wherein the trouble lies, a timer for causing the device to operate at the proper time, and a secondary circuit that may be installed between the low voltage circuit and the motor controlling circuit which may be used with very large motors.

Other features and advantages of the invention will appear from the following description taken in connection with the drawings, wherein:

Figure 1 is a diagrammatic view showing the circuits as they may be connected to the controller box.

Figure 2 is another diagrammatic view showing an alternate arrangement where a secondary circuit may be used between the low voltage or battery circuit and the motor controlling circuit for large motors.

In the drawings we have shown our device as it would appear wherein numeral 1 indicates the controller box of an automatic or button controlled motor, numeral 2 a magnet or relay that may be installed in the stop circuit to operate it in a manner similar to that in which it is operated when the stop button is pushed, numeral 3 a bank of switches to determine which of the auxiliary circuits has been completed, and numeral 4 a timer for closing the auxiliary circuits at predetermined intervals.

The controller box 1 may be constructed as shown with a solenoid 5 for raising the rheostat arm 6 and a magnet or relay 7 for breaking the main circuit through the points 8 and 9 as the stop circuit is broken.

An arm 10 may be attached to the rheostat arm 6 through a bar of insulation 11 and a pivot pin 12, and the upper end of this arm has an extension 13 on it which projects through an opening 14 in a plate 15. The plate 15 is attached to a bar of insulation 16 which is held to the controller box by screws 17 and on the upper side of the plate 15 is a spring plate 18 and a contact point 19 with insulation 20 between them. A post 21 is placed on contact point 19 to which one of the wires of the auxiliary circuit may be connected, and the contact point 18 may be grounded or connected into the auxiliary circuit as shown. It will be seen that when the rheostat is off, the upper end of the arm 10 will hold the spring plate down as shown, and when the rheostat and motor are on, the arm 6 will move upward and the upper end of the arm 10 will move to the position

shown in dotted lines so that the spring plate 18 may move upward to the position shown in dotted lines and form a contact with the outer end of the contact point 19.

5 This will form a contact between the wires 22 and 23 which are in an auxiliary circuit that operates the magnet 2. The wire 22 may have a battery 24 in it or may be connected in any low voltage circuit as may be 10 desired.

The wire 23 will extend to any number of contact points which may be placed on a machine or in a shop in any desired manner. Should it be desired to use the machine as a 15 ground for a low voltage circuit the insulation 16 may be replaced by metal so that a ground connection would be made directly to the machine and in this case the points 25 may be connected to the machine or may be 20 parts of the machine. Levers 26 may also be placed upon the machine or in any desired location and will be arranged so that as trouble develops they will be moved until they engage the points 25, or when the 25 machine is used as a ground these levers 26 may be set so that they will be forced against a part of the machine when trouble of any nature occurs. Wires 27 extend from the levers 26 to terminals 28 in the bank of 30 switches 3 and other wires 29 may extend from the opposite terminals 30 of the switches to a common wire 31 which connects them with a main switch 32. The main switch 32 is connected to the magnet or relay 35 2 by a wire 33 and the opposite terminal of the magnet or relay is connected to the wire 22. It will be seen that as the switches 3 are set so that they will engage both of the terminals 28 and 30 and as the plate 18 is in 40 contact with the plate 19 this auxiliary circuit will be complete with the exception of the points 25 and 26; and then as these points are brought into engagement by trouble in the line or in the case of the machine being 45 used as a ground by one of the points 26 being forced against a part of the machine, while the controller arm 6 is up in the operating position the low voltage circuit will be completed and the magnet or relays 2 energized.

50 As the magnet or relay 2 is energized it will draw the contact point 34 away from the point 35 and break a circuit which may be the ordinary stop circuit of the motor. 55 We have outlined this circuit by showing a stop button 36 connecting terminals 37 and 38 and having a wire 39 extending from the terminal 37 to the point 35, a wire 40 extending from the contact point 34 to a power line 41 and a wire 42 extending from the terminal 38 to the magnet 7. The opposite terminal of the magnet 7 is connected by a wire 43 to the solenoid 5 and the opposite terminal of the solenoid is connected by a 60 wire 44 to the power line 41. The wire 43

is also connected by a wire 45 to the contact point 8 of the relay 7 and also by a wire 46 to a terminal 47 of the starting button 48, the opposite terminal 49 of which is connected by a wire 50 to a power line 51 and 70 also by a wire 52 to the contact point 9 of the relay 7.

75 It will be seen that as the starting button 48 is pushed downward it will complete a circuit from the power line 51 through the wires 50, 46, and 43 to the solenoid 5 and through the wire 44 from the solenoid to the opposite power line 41. Another circuit will also pass from the power line 51 through the wires 50, 46, and 43, the magnet 7, the wires 89 42, 39, and 40 to the opposite power line 41, which circuit will pass through the stop circuit and energize the magnet 7 which will hold the contact points 8 and 9 into engagement and permit the motor controlling circuit to pass from the power line 51 through the wires 50 and 52, the points 8 and 9 and the wire 45 to the solenoid and from the solenoid through the wire 44 to the opposite power line 41. This will constitute the running circuit as the starting button 48 is instantly released as soon as the magnet 7 is energized and contact points 8 and 9 brought into engagement; and it will be seen that as soon as the auxiliary circuit is completed 95 and the magnet 2 energized the point 34 will be drawn away from the point 35 and the stop circuit which passes through the magnet 7 will be broken so that the contact point 8 will drop away from the point 9 and the machine will then remain idle until the starting button 48 is again pushed downward.

A timer 4 may be placed in any of the auxiliary circuits and may be set so that it will only be possible to complete the circuit 105 at predetermined intervals, as in the case of objects moving through a passage there may be regular spaces between the objects, and the timer may be set so that the circuit may only be completed when it is time for the objects to pass between or engage the points.

110 In the design shown in Figure 2 we have shown a secondary circuit that may be installed between the low voltage or battery 115 14 and the motor controlling circuit, or between the magnet 2 and the contact points 34 and 35, as when a very large motor is used the low voltages or battery circuit may not be strong enough to break the contact points and therefore it may be found necessary to operate a secondary circuit by the low voltage or battery circuit and have the secondary circuit operate the controlling circuit. The magnet 2 may be connected to the wires 22 and 33 of the auxiliary circuit in 120 the same manner and as the magnet is energized it will draw a contact point 53 into engagement with the point 52 which will complete a circuit from the power line 41 through the wire 54, the points 53 and 52, a 125 130

wire 55, a solenoid 56 and a wire 57 to the opposite power line 51. As this circuit is completed the magnet 56 will draw the contact point 34 away from the point 35 and break the stop circuit as hereinbefore described.

It will be understood that changes may be made in the construction without departing from the spirit of the invention. One of which changes may be in the design of the switch formed by the contact points 18 and 19, or in its location, or in the means for operating it; another may be in the use of a different means for operating the arm 6; and still another change may be in the design or location of the switches formed by the contact points 25 and 26, as it is understood that these may be of any suitable design and may be located at any suitable points.

The construction will be readily understood from the foregoing description. To use the device it may be arranged and installed in a machine, shop, building or any suitable location and the contact points 25 and 26 set so that they will either make or break the circuit as trouble or anything unusual occurs. The device may also be set to stop a machine at the end of a predetermined time or after a predetermined number of objects or amount of material has passed through as the last object passes through the contact points 25 and 26 may engage or disengage and stop the motor. It will be seen that with a device of this type it will be possible to stop a machine instantly on very delicate work as by having a low voltage circuit passing through the points 25 and 26 it will be possible to set them very accurately without danger of them fouling, and therefore, it will be particularly adaptable to machines similar to newspaper assembling machines as it will be possible to set any number of pairs of the points 25 and 26 all over the machine and as sections of paper of the wrong thickness pass through the different stages the points will engage or disengage, as the case may be, and instantly stop the machine. The timer 4 may be set so that at predetermined intervals certain sections of the paper may or may not pass through a certain stage without stopping the machine. This flexibility of the device will make it possible to positively and automatically govern the most minute movement of the machine. When trouble has developed the switches 3 may be set so that they may be engaged or disengaged individually which will make it possible to quickly determine which circuit the trouble is in. Furthermore, it will

be seen that as soon as the device stops the motor the auxiliary circuit will instantly be broken by the separation of the points 18 and 19 so that the entire system may instantly return to the position ready for starting.

Having thus fully described the invention what we claim as new and desire to secure by Letters Patent, is:—

1. A magnet means for making or breaking the controlling or stop circuit of an automatically controlled motor, a circuit controlling said magnetic means and a means for making or breaking said controlling circuit, said means being operative by the operation of the motor controller.

2. A means for automatically breaking the controlling circuit of an automatically controlled motor comprising a magnet; contact points adjacent the magnet which will open as the magnet is energized and close as the circuit is released; automatic switches in the said magnetic circuit which will operate when trouble develops and energize the magnet and a means for automatically releasing said auxiliary circuit as the controlling circuit is broken.

3. In a motor controller, an auxiliary circuit connected in the stop circuit of the controller, a magnetic means in the auxiliary circuit to operate the stop circuit to stop the motor as the magnetic means is energized, and a means in the said auxiliary circuit for de-energizing the said magnet, and thereby placing the motor in the position ready for starting as soon as the motor is stopped.

4. In a means for automatically stopping the motor, a stop circuit, a switch in the said stop circuit, a means for operating the said switch, an auxiliary circuit connected to the said switch operating means, a switch in the auxiliary circuit, means for closing the said switch as the motor is started, and for opening the said switch as the motor stops and means in the said auxiliary circuit for completing a circuit therethrough, and thereby operating the said switch operating means as an unusual condition develops.

5. In a means for automatically stopping a motor, a stop circuit, an auxiliary circuit, a means in said auxiliary circuit for causing the circuit to be closed as the motor is running and opened when the motor is stopped, a means for closing said auxiliary circuit as an unusual condition develops and a means for operating said stop circuit of the motor by the said auxiliary circuit.
